UNITED STATES PATENT OFFICE.

HARRY L. ALLEN, OF ALLIANCE, OHIO, ASSIGNOR TO AMERICAN STEEL FOUNDRIES, OF NEW YORK, N. Y., A CORPORATION OF NEW JERSEY.

SIDE FRAME.

1,165,740.

Specification of Letters Patent. Patented Dec. 28, 1915.

Application filed August 7, 1915. Serial No. 44,220.

To all whom it may concern:

Be it known that I, HARRY L. ALLEN, a citizen of the United States, and resident of Alliance, in the county of Stark and State 5 of Ohio, have invented certain new and useful improvements in Side Frames, of which the following is a specification.

My invention relates to car trucks, and has particular reference to a novel side frame 10 for use in connection therewith.

It has been found desirable and expedient to form the side frames of car trucks as a single casting. However, as these castings are made in steel, many difficulties have been 15 experienced in the production of sound castings and in the provision of a design which shall at the same time permit of the production of sound castings and give requisite strength vertically and transversely.

20 In the construction shown, an object is to provide a side frame which may be cast to advantage and which shall combine the requisites of lightness and strength against vertical and transverse stresses. This result is 25 secured by adopting the closed box form for the entire frame. In other words, the casting comprises in effect two vertical webs of the proper shape, which webs are joined by transverse webs, thus forming a closed box 30 at any points through which a section is taken.

The invention will be more readily understood by reference to the accompanying drawings, wherein—

35 Figure 1 is a front elevation of a side frame constructed in accordance with my invention; Fig. 2 is a plan view thereof, and Fig. 3 is a section on the line 3—3 of Fig. 1.

40 Referring more particularly to the drawings, it will be seen that the side frame consists essentially of a casting having a compression member 10, tension member 11, struts 12 and journal box engaging portions 45 13. Described in that way, the frame comprises two webs of the shape shown in Fig. 1, one web being disposed behind the other, and these webs being joined by transverse webs to form an integral structure having a cored or hollowed out interior. As a means 50 for setting the cores and cleaning the cast-

ing, I may provide the transverse openings 14 and the vertical openings 15, the latter being formed in the compression member 10. Similar openings 16 will be provided in the end pieces 13, for the accommodation of 55 journal box bolts. To permit the entrance of the journal box bolt, I cut out a portion of the compression member at the ends, as indicated at 17, 18, in Fig. 2. Brake hanger lugs 19 are integrally formed with the east- 60 ing.

The construction is capable of some modification, and such modifications as are within the scope of my claims I consider within the spirit of my invention.

65

I claim—

1. In a side frame, the combination of a compression member, tension member and strut arranged in truss form, the structure of said parts including two webs shaped to 70 the form of the side frame, the edges of the two webs being joined by continuous webs, thereby producing a box-shaped beam and provided in its compression and tension members with openings, said openings serving as a means for supporting the cores and for cleaning the sand from the interior of the box after the casting has been formed, substantially as described.

2. In a side frame, the combination of a 75 compression member, tension member and strut, the structure of said parts including a pair of webs formed to the shape of the casting desired, the bounding edges of said webs being joined by lateral webs, thereby producing a complete truss-shaped structure, a section through any member of which is in the form of a box, said casting being provided in its compression and tension members with openings which serve to permit of 80 the use of means for supporting the cores and for cleaning the casting, substantially as described.

Signed at Alliance, Ohio, this 29th day of July, 1915.

HARRY L. ALLEN.
